UNITED STATES PATENT OFFICE.

GEORGE S. McFARLAND, OF COLUMBUS, OHIO.

METAL-TREATING CONTAINER.

Application filed June 17, 1925. Serial No. 37,684.

This invention relates to metal treating containers and is particularly concerned with the provision of a container of novel construction for employment in the heat treatment of metals. More particularly, this invention relates to a container which may be used in metal treating processes where high temperatures are employed, a typical illustration of which is the cementation or carburizing process, wherein metals are heated to a high temperature in the presence of some material which supplies carbon to the metal and results in imparting a very hard exterior shell or case to the metals treated.

Heretofore, it has been the practice to pack the articles to be treated in relatively thick metal containers which are usually of integral construction. The great thickness and weight found necessary to resist the scaling, oxidation and corrosion to which these containers are subject and make them more durable, necessitates a longer time in processing, increased fuel consumption, and consequently an increase in the manufacturing cost of the articles treated.

One object of my invention is the provision of a container or shell for the heat treatment of metals designed to be positioned within a supplementary container or basket. This container or shell may be manufactured from a non-scaling, non-corroding and non-oxidizing rolled or sheet metal which makes possible the use of containers or shells of thinner and lighter material. Such a container or shell also has a much longer period of usefulness, is lighter in weight and therefore easier to handle and store, requires less time and fuel in heating, and is not subject to cracking, warping or distortion. It further insures a better product because the heat conductivity is uniform over the entire surface and is not variable because of the non-uniform deposition of refractory scale over parts of the container.

A further object of my invention is the provision of a basket or supplementary container having removable and replaceable members to fit therein to contain the carburizing material and articles to be treated. The great temperature at which the carburizing process is conducted may eat away and disintegrate the shells after relatively short periods of service, but by providing

a permanent supplementary container or basket having removable shells which may be disposed of when they become unserviceable and replaced by new ones at a small cost I greatly reduce the cost of maintaining the equipment. The basket device does not come into contact with the carburizing material and therefore does not appreciably disintegrate or become otherwise unserviceable.

Various other objects of my invention will be apparent as this description progresses, and will be brought out in the claims appended hereto. The various objects of my invention are preferably obtained by the structure illustrated in the accompanying drawings, wherein similar reference characters designate corresponding parts and wherein,

Figure 1 is a perspective view, partly broken away, showing the different parts of my device in assembled position.

Figure 2 is a plan view of the container or shell.

Figure 3 is an elevation of the container or shell shown in Figures 1 and 2.

Figure 4 is a plan view of the lid or cover.

Figure 5 is an elevation of the lid or cover shown in Figure 4.

In the drawings, and with particular reference to Figure 1, my invention is shown as comprising the preferably open-ended tube, shell or container 1 which may be of any desired shape depending upon the articles to be treated, or upon the preferences of the user. This tube or shell member is desirably manufactured from relatively thin rolled or sheet metal, and the abutting edges united by any suitable means such as the lap seam shown, which may be so formed as to permit the shipment of the container or shell in a flat position so as to occupy less space and permit a large number to be packed in one container. The edges may be united by pressing, rolling, or in any other suitable manner at the place of use of the containers. This seam, in addition to uniting the abutting edges, also serves as a strengthening rib which tends to prevent distortion when the container is heated.

It is understood that my invention contemplates the use of seamless tubing or of tubing formed with integral ribs or reinforcements where such are desirable. It is also understood that this container may be

formed into any of the common shapes and may be provided with an integral or attached base or with a central core such as is commonly used in the treatment of certain articles. The material from which this container is manufactured is preferably a non-scaling metal, such as chromium, nickel or chrome-nickel alloy which will not oxidize or corrode at the temperature of use, but for 10 reasons hereafter explained, a common rolled or sheet metal may be used. The heat resisting alloys have the advantage of being able to withstand long and continuous use without appreciable deterioration, whereas 15 common rolled or sheet metal is relatively cheaper and may be economically employed due to the fact that I have provided a permanent basket or supplementary container which is not subject to deterioration and in 20 which the containers or shells may be placed.

The container 1 is shown mounted in the basket or supplementary container 2 which may be formed with the legs 3 and preferably open-work or retiform bottom 4. The 25 vertical ribs 5 may be encircled or connected by one or more members 6 to retain the shell or container 1 and prevent distortion thereof. The retiform or open-work construction of the sides and bottom permit the 30 heat to have easy access to the relatively thin metal of the container 1 and base and to immediately begin its work of metal treatment without first penetrating any thick metal containers. The basket 2 makes possible 35 the use of containers of common sheet metal which, although not so durable as containers manufactured from the heat resisting metals, are very cheap and may be replaced at small cost while the basket will last almost indefinitely.

It will be understood that this basket may be fabricated in any desired shape and from any suitable material and the design and proportions of its various parts may be varied 45 extensively but all such modifications are within the scope of my invention. This basket or supplementary container is preferably formed of some heat resisting metal such as the alloys of chromium, nickel, 50 chrome-nickel, etc., and may be cast in one integral piece or built up of one or more pieces.

A lid or top 7, shown in Figures 1, 4 and 55 5, is intended to loosely interfit with the container and may be luted thereon by clay or other suitable lute. This cover is preferably formed to permit of the alternate use 60 of its opposite sides adjacent the interior of the container to thereby avoid warping which the ribbed construction will also tend to prevent. This lid is intended to prevent escape of gases during the heat treatment 65 since it has been found that such gases when confined within the container will expedite the treating process. This lid also

has the further purpose of excluding air, which would probably oxidize and detrimentally affect the objects being treated.

The particular form of lid shown or the method of sealing is not intended as a limitation of the use of my invention as other methods of sealing are in common use and may be employed, and still retain the fundamental principles of my invention.

In use, the various parts are assembled, 75 as shown in Figure 1. A bottom plate 8 rests loosely upon the open-work bottom of the basket 2, the container or shell 1 is positioned within the basket or supplementary container and rests upon the bottom plate 8 to which it may be luted. The lid 7 is positioned upon the top of the shell or container. By providing the supplementary container 2 with a solid instead of retiform bottom, the bottom plate 8 may be dispensed 85 with. This arrangement provides a very compact and easily disassembled structure with which containers of ordinary sheet metal may be used and economically replaced, or containers of heat resisting metal 90 used to obtain the objects heretofore discussed.

From the preceding description, it will be obvious that I have produced a container for the heat treatment of metals which may be 95 cheaply manufactured from thin, light rolled metal of a quality to resist scale, oxidation and corrosion and a container which will outlast many of the ordinary variety if the heat resisting metal container or shell is 100 used, or if a container of ordinary rolled metal is used, it makes possible the economical replacement thereof after a comparatively short period of service. The device is light in weight, easily handled and 105 stored, requires less fuel for a given treatment, fewer laborers are required to handle it, the heat conductivity is uniform over the entire surface, the initial cost is less than for other containers, the treatment is expedited, and the product is improved in quality 110 because the elimination of unknown or variable values makes possible better control of the treatment, and finally the cost of the treating process is reduced. The term heat 115 treatment as used in this specification comprehends such processes or operations as carbonizing, cementation, annealing, malleabilizing, etc., wherein high temperatures are employed in the treatment of metals.

Having thus described my invention, what I claim is:

1. In a carbonizing vessel, a frame of material resistant to heat, and a removable container mounted within said frame, the latter being adapted to be replaced when it has become useless without replacement of the said frame.

2. A carbonizing vessel comprising a frame made of a material resistant to and

substantially unaffected by high temperatures, and a removable container mounted within said frame, the latter being made of a material non-resistant to and readily affected by high temperatures.

5. A carbonizing vessel comprising a basket-like frame made of a metal resistant to and substantially unaffected by high tem-

peratures, and a removable container of sheet metal mounted within said frame, the 10 latter being made of a metal non-resistant to and readily affected by high temperatures.

In testimony whereof, I hereby affix my signature.

GEORGE S. McFARLAND.
